UNITED STATES PATENT OFFICE.

THOMAS JAMES BROUH, OF BALTIMORE, MARYLAND.

BAG-CLOSING MACHINE.

No. 874,734.

Specification of Letters Patent.

Patented Dec. 24, 1907.

Application filed May 11, 1907. Serial No. 373,181.

To all whom it may concern:

Be it known that I, THOMAS JAMES BROUH, a citizen of the United States, and resident of Baltimore, in the State of Maryland, have invented an Improved Bag-Closing Machine, of which the following is a specification.

My invention is an improved machine for closing or tying the mouths of paper and other bags filled with tea or other commodities put up for sale in small quantities. The closure is effected by means of flexible wire which is passed around and compressed and clamped upon the gathered mouth of a bag, the wire being fed automatically and intermittently as required, and the portion applied to the bag being severed at the proper time.

The details of construction, arrangement, and operation of parts are as hereinafter described, and illustrated in the accompanying drawing, in which—

Figure 1 is a side view of the machine, a portion being broken away to illustrate certain details. Fig. 2 is a vertical section on the line 2—2 of Fig. 1. Fig. 3 is a vertical section on the line 3—3 of Fig. 1. Fig. 4 is a plan view of the machine. Fig. 5 is an enlarged longitudinal and vertical section of the central portion of the machine showing particularly the means for bending and clamping the wire upon a bag. Fig. 6 is a perspective view of the knife or cutter for severing the wire. Fig. 7 is a section showing substantially the same parts as Fig. 5 but illustrating a further step in the operation of bending the wire and clamping it upon a bag. Fig. 8 is a horizontal section (looking upward) on the line 8—8 of Fig. 1. Fig. 9 is a vertical section on the line 9—9 of Fig. 1. Fig. 10 is a plan view of the friction wire-feed apparatus.

The working parts of the machine are applied to, or suspended from, a horizontal platform, or table, 1, which may be supported by legs 2, or any other suitable means. A double crank-shaft 3 is journaled in the lower ends of hangers 4, see Figs. 1 and 2, which are pendent from one end of the platform 1. This shaft may be driven by hand or power, as preferred, or as found expedient. From it the required movements are imparted to all the other movable portions of the machine. The wire α , by which a bag closure is effected, is

fed intermittently by means of friction rollers 5, 5, which, as shown in Figs. 1, 3, 10, are arranged side by side and provided with meshing gears 6, the same being mounted on axles 7, which are connected by spiral springs 8, 60 and have their bearings in vertical supports 9 attached to a horizontal bar 10, that connects the lower portions of the legs 2. It is obvious the springs 8 hold the feed-rolls 5 in firm contact with the wire α , and that, 65 when one is rotated, the other is necessarily rotated also. The required rotation for feeding the wire α intermittently is effected by a bar or rod 11, which is operatively connected with the crank shaft 3, its free end 70 being supported in a guide on one of the legs 2, and provided with pivoted dogs or pawls 12, which engage the gears 6 but are pointed in opposite directions. Thus, when the bar or rod 11 is reciprocated, one of the 75 pawls will rotate one of the gears and thereby effect the rotation of both feed rolls 5, while the other pawl will drag on the opposite gear. The bar 11 is pivoted to a lever 13, see Fig. 1, journaled on a transverse rod 14 fixed in the middle portions of the hangers 4. The forked lower end of said lever straddles a crank of shaft 3. To the upper end of this lever 13 is pivoted a pawl rod 15, see Figs. 1 and 8, which engages a ratchet wheel 16 mounted upon a wire guide 17, see also Fig. 5. The latter is a tube extending through a suitable bore in the table or platform 1 and its upper end being flush with the latter. It is apparent that as the crank shaft 3 is rotated, the forked lever 13 will be oscillated and thus not only impart intermittent feed to the wire α but also impart intermittent rotation to the guide 17 through the medium of the pawl and ratchet 15 and 16. The object of rotating the guide 17 is as follows. The wire α passes from said guide into a curved former 18, which is formed at the end of a block 19 secured upon the platform or table 1, but spaced therefrom sufficiently to permit the insertion and operation of a wire cutter 20. This cutter coacts with the top or head of the wire guide 17, which, if held constantly in one 95 position without rotation, would become worn and the metal would be to a certain degree upset; whereas, by the constant intermittent rotation of the guide, the wear is made uniform and the knife or cutter 110

thus acts in the most effective manner in severing the wire. It will thus be seen that the part 17 subserves two purposes in the operation of the machine.

5 The cutter 20 lies flat upon the table 1 and is provided with a lengthwise slot 21, see Fig. 4, and through said slot passes a bolt 22. The cutter is connected by a slotted lug 23, see Fig. 1, with a lever 24, 10 whose lower end is pivoted on a cross-rod 25, see Fig. 3, and which is oscillated in a vertical plane by a rod 26 that connects it with a forked lever 13^a pivoted, like the lever 13, on the cross rod 4, and forked at 15 its lower end for connection with one of the cranks of the shaft 3. The upper end of said lever extends through a slot in the platform or table 1, see Fig. 4, and is pivoted to a wire-clamping bar 28 arranged 20 horizontally on the table and adapted to slide in a keeper 29. The inner or free end of the bar 28 is opposite the curved former 18, before referred to, and by its coaction with such former constitutes an essential 25 factor in the operation of bending and clamping the wire around the mouth of the bag.

As shown in Fig. 5 and 7 the wire-bending and-clamping bar 28 is supported near its 30 free end upon a set-screw 28^a, which passes up through the table 1. This device serves as a means for raising and lowering the bar 28 and thus adjusting it exactly as required for the most effective coaction with the 35 former 18.

As the wire is fed or advanced by the rolls 5 through the rotating guide and die 17, it passes up within the curved former 18, as shown in Fig. 5, and is gradually bent or 40 curved as there indicated, its free end coming finally in contact with a shoulder of the former. The bag whose mouth is to be closed is laid by hand upon the platform or table 1, and in the position indicated by dotted 45 lines Fig. 4, with the mouth of the same gathered and inserted within the former 18. Thus the wire in the position shown has already passed more than half of the distance required to encircle the mouth of the bag. The coacting bar 28 now advances 50 and by means of a spring arm 30 attached to and standing above its free end, a pusher, or sliding bolt, 31 arranged vertically in guide 18, see Figs. 5, 7, is forced down so that the 55 free end of the wire is bent downward, and, being simultaneously further advanced, it passes around the mouth of the bag, and the bar 28, still advancing, it is clamped on the bag and thus closes the mouth of the 60 same. In Fig. 5 the first stage of the operation is illustrated, and in Fig. 7, the latter or succeeding stage. The pusher 31 is shown normally supported by a spring 32 and is provided with a rounded and enlarged head, 65 upon which the spring arm 30 rides up as

shown. The cutter 20 advances almost simultaneously and severs the portion of the wire which has been thus applied to the bag. Practically at the same time, cutters 33 and 34, see Figs. 1 and 4, are advanced for cutting off the surplus projection or portion of the bag extending beyond the closure. These cutters consist of elongated blades which are arranged in guides 19 and 29 respectively, their inner ends being beveled 70 and otherwise so constructed as to act with the best effect on the bag mouth and also to pass each other in the cutting operation. As shown, the cutter 34 is forked at its cutting end, while the other is slightly inclined. 75 The cutter 33 is reciprocated by the connection effected by pendent arm 35, see Fig. 1, and a rod 36, whose left end is pivoted to a lug formed on the forked lever 13. The other cutter 34 is also reciprocated through 80 its connection with said lever 13, which connection is established—see Fig. 1—by rod 37 and the vertical lever 38, the latter being pivoted on a lug 39, and its upper end having a slot 40 that receives a pin on the cutter 34. 90 Thus as the crank shaft 3 rotates, the lever 13 is oscillated, and thereby reciprocates cutters 33 and 34 simultaneously, and in opposite directions. It is necessary in order to utilize the whole cutting edge of cutter 20, or avoid cutting always at one point, that the cutter shall be oscillated or shifted laterally, and for this purpose I employ 95 the following mechanism. A rod 37^a—see Figs. 4 and 6—is arranged in a transverse 100 slot in the table 1, and attached to a lever 38^a pivoted to table at 39^a. This lever 38^a is operatively connected by a slotted bar 40 with a cam forming an attachment of a horizontal ratchet wheel 42. It is obvious 105 that the rotation of the ratchet and consequent rotation of the cam 41 will impart oscillation to the lever 38^a and thereby reciprocate the bar 37^a, which, in turn, will move the cutter 20 on the pivot 22 in such manner 110 as to constantly shift the cutting point from one side of the cutting edge to the other, and reversely. For thus rotating the ratchet 42 I employ means connected with the lever 24; see Fig. 1. Such means consist of an 115 elbow lever 43 pivoted at 44 on an arm or bar 45, pendent from the table, and one arm of the same being connected by a rod 46 with the lever 24, while the other or shorter arm of the lever is connected by a rod 47 with a 120 slidable bar 48, see Fig. 4, the latter being provided with a pawl or dog 49, adapted to engage the ratchet 42. It is obvious that the reciprocation of the bar 48 will impart 125 intermittent rotation to the ratchet and thereby to the cam as before described. A spring dog 50 is applied to the ratchet to prevent its backward rotation.

I claim—

1. The combination with a table, an inte- 130

riorly curved former arranged thereon and a movable wire-compressing device coacting therewith, of a reciprocating cutter arranged beneath the said former, and means for advancing it for severing the wire after the same has been applied to the bag for closing it, substantially as described.

2. The combination with a former and means for advancing the wire thereinto, of a movable device for compressing the wire upon the mouth of a bag, a wire cutter applied beneath the former, means for reciprocating the cutter, and means for shifting the same laterally for distributing the wear on 15 the cutting edge, substantially as described.

3. The combination with a former and means for feeding a wire thereinto and compressing it as described, of a wire cutter and means for reciprocating it, a ratchet-and- 20 cam mechanism operatively connected with the beveled end of the cutter, whereby it is moved intermittently laterally while being reciprocated, substantially as described.

4. The combination with means for feeding and bending and clamping a wire upon the mouth of a bag, of a cutter adapted to reciprocate and work in contact with the projecting end of the bag, and means for imparting movement thereto, substantially as 30 described.

5. The combination with a former and means for advancing a wire thereinto and clamping it upon a bag, of reciprocating cutters arranged horizontally opposite each 35 other and means for reciprocating the same whereby they are advanced simultaneously in opposite directions for severing the projecting end of a bag, substantially as described.

40 6. The combination with an interiorly curved former, means for advancing a wire thereinto, and a reciprocating device for clamping the wire upon the mouth of a bag, of two reciprocating cutters arranged on the 45 side of said former, and means for operating the same consisting of levers and rods connected and adapted to operate, substantially as described.

7. The combination with means for curving and clamping a wire upon a bag, of a wire guide and die having a central bore through 50 which the wire is fed, means for imparting rotation to such guide, and a reciprocating cutter adapted to coact with the upper end

of the guide for severing a wire in the manner described.

8. The combination with means for applying a wire to the mouth of a bag and clamping it thereon, of means for advancing the wire, a rotatable guide through which the same passes, lever and pawl and ratchet mechanism for imparting rotation to said guide, and a cutter adapted to coact with the guide for severing the portion of the wire applied to a bag, as shown and described.

65 9. The combination with means for feeding a wire and clamping it upon the mouth of a bag, of a rotatable guide and die through which the wire is fed and a cutter adapted to slide over the head of said guide and die, and means for rotating the latter, substantially as described.

70 10. The combination with means for bending and clamping a wire upon the mouth of a bag, of means for advancing such wire, the same comprising friction rolls arranged opposite each other and provided with meshing gears, and a double-pawl feed consisting of a slidable bar having pawls projecting in opposite directions and adapted 75 for engaging and sliding over the gears alternately, and means for reciprocating the feed, substantially as described.

80 11. The combination with means for applying a wire to a bag, of means for feeding such wire, the same comprising two cylindrical rolls arranged opposite and provided with meshing gears, slotted bearings for the axes of the rolls, springs applied to the axes and serving to hold the rolls and gears normally 85 in contact, and means for imparting rotation to the rolls, substantially as described.

90 12. The combination with means for feeding a wire and curving the free end of the same and clamping it upon a bag, of slidable cutters arranged opposite each other in a vertical plane and means for advancing them toward each other when the wire has been clamped on the bag, the same consisting of an actuating shaft, a lever oscillated thereby, and rod-and-lever mechanism connecting the first-named lever with the ends of the respective cutters, substantially as described.
